UNITED STATES PATENT OFFICE.

JAMES I. GEMMILL, OF PONTIAC, MICHIGAN, ASSIGNOR OF ONE-HALF TO WM. A. LUDLOW, OF PONTIAC, MICHIGAN.

VALVE MECHANISM FOR INTERNAL-COMBUSTION ENGINES.

Application filed January 31, 1924. Serial No. 689,730.

To all whom it may concern:

Be it known that I, JAMES I. GEMMILL, a citizen of the United States of America, residing at Pontiac, in the county of Oakland 5 and State of Michigan, have invented certain new and useful Improvements in Valve Mechanism for Internal-Combustion Engines, of which the following is a specification.

10 This invention relates to new and useful improvements in valve mechanism for internal combustion engines.

15 The primary object of the invention is to provide a system of valves of the above mentioned type which are positively operated through all of their cycles of motion with reference to the rotation of the main rotating member of said engine and without springs or other returning agency as is common 20 in other mechanisms of like kind.

25 A further object of the invention is to provide a valve and operating mechanism that may be thoroughly lubricated, highly efficient and actually noiseless.

30 30 A further object of the invention is to provide fuel passages of generous capacity which are at all times filled with fuel and are completely surrounded by a hot water jacket which receives its supply of hot water from the water jacket surrounding the power cylinders, thereby assuring a warm, dry 35 charge of explosive mixture.

35 Other objects and advantages of the invention will be apparent during the course of the following description.

40 In the accompanying drawing forming a part of this specification and in which like numerals are employed to designate like parts throughout the same,

45 40 Figure 1 is a vertical sectional view, partly in elevation, of an internal combustion engine and shows more clearly the inlet and exhaust valves and the mechanism employed for operating the same, and Figure 2 is a side elevational view, partly broken away, of the engine illustrated in section in Fig. 1.

50 In the drawing, wherein for the purpose of illustration is shown a preferred embodiment of the invention, the numeral 5 designates a crank case of any usual form and having mounted thereon a cylinder block 6 having a power cylinder 7 formed therein which is open at each end and communicates with the crank case 5 at its lower end. 55 Formed in the cylinder block 6 and sur-

rounding the power cylinder 7 is a water jacket 8 which is open at its upper end. Mounted upon the upper end of the cylinder block 6 and suitably secured thereto is a two-part cylinder head, there being 60 provided a suitable gasket 9 between the two-part cylinder head and the upper end of the cylinder block 6 for the well known purpose of preventing the escape of the cooling medium and compression.

65 This two-part cylinder head consists primarily of a lower part 10 which is formed by a suitable casting operation and an inverted pan-shaped upper part 11. Tubular connecting bolts 12, having screw threads 70 formed on each end thereof, are suitably connected, as at 13, to the lower part 10 and extend upwardly through the upper inverted pan-shaped part 11 and projects slightly 75 outwardly from the upper surface thereof for the purpose of receiving the compression nuts 14. It will be seen that these tubular connecting bolts 12 provides means for separably connecting the two parts of the cylinder head.

80 It is to be understood that any suitable means may be employed for preventing leakage between the points of connection of the two parts of the cylinder head.

85 It will be seen, by inspecting Fig. 1, that the cast lower part 10 of the cylinder head is formed with a substantially inverted cup-shaped pocket or recess 15 in its lower face that is located in axial alinement with a power cylinder 7 formed in the cylinder block 6 and acts as an extension of the same, 90 it being understood that each cylinder is formed in the same manner. Positioned directly above this inverted cup-shaped pocket or recess 15 is a relatively small chamber 16 which communicates with the said pocket or recess 15 and the power cylinder 7 through a throat or restricted passageway 17. This chamber 16 will be referred to, from now on, as the explosion chamber. Formed in the inner part 10 of the cylinder head directly above the explosion chamber 16 is a 95 well 18 which is positioned in axial alinement with the bore of the tubular connecting bolt 12. An internally screw-threaded passageway 19 connects the well 18 and the explosion chamber 16 and is adapted for receiving the externally threaded bushing of the spark plug 20. It will be seen by this arrangement that the electrodes of the spark plug 20 are positioned within the explosion

100 105 110 plug 20 are positioned within the explosion

chamber 16 and that the said spark plug may be properly positioned as shown by employing the bore of the tubular connecting bolt 12 and by utilizing a suitable tool in the form of a tubular socket wrench. The bore of the tubular bolt 12 also may be employed for receiving an ignition wire connected to the spark plug 20.

Positioned laterally on opposite sides of the explosion chamber 16 and well 18 are the valve cylinders 21 and 22, the valve cylinder 22 being termed the inlet valve cylinder and the cylinder 21 being termed the exhaust valve cylinder. Passageways 23 and 24 are formed in the lower cylinder head part for connecting the exhaust valve cylinder 21 and the inlet valve cylinder 22 with the explosion chamber 16. It will be noted that these passageways 23 and 24 are arranged substantially midway of the length of the valve cylinders 21 and 22. An inlet passageway 26 is also formed in the lower part 10 of the cylinder head and forms means for the admission of fuel into the inlet valve cylinder 22. An exhaust passageway 25 is formed in the opposite side of the lower part 10 and provides means for permitting the exhausting of the exploded gases from the exhaust valve cylinder 21. It will be noted that the inlet and exhaust passages 26 and 25 are arranged at the lower ends of the inlet and exhaust valve cylinders 22 and 21 respectively.

Positioned within the inverted pan-shaped upper part 11 of the cylinder head and extending horizontally adjacent opposite side walls of the same are the crank shafts 27 and 28 which are arranged in vertical alignment with the axes of the valve cylinders 21 and 22. It is to be understood that these crank shafts 27 and 28 may be suitably journaled in the upper part 11 or journaled in suitable brackets *b* carried by the upper face of the lower cylinder head part 10. The crank shafts 27 and 28 are provided with crank portions 29 which are operatively connected to the pitmans 30 which in turn are connected to the vertically reciprocating piston valves 31 and 32. It will be seen by this arrangement that the rotation of the crank shafts 27 and 28 will cause the piston valves 31 and 32 respectively to reciprocate within the valve cylinders 21 and 22 for opening and closing the passages 23, 24, 25 and 26 for controlling the inlet of fuel and the exhausting of exploded gases to and from the explosion chamber 16. There is positioned within the upper inverted pan-shaped cylinder head part 11 an additional shaft 33 which extends horizontally and is arranged slightly above and between the crank shafts 27 and 28. It is to be understood that this shaft 33 does not extend all the way through the upper part 11, but terminates short of the first tubular connecting bolt 12. This

shaft may be suitably journaled in a depending bracket carried by the upper wall of the inverted pan-shaped part 11, or the front bracket *b* and additional bracket *c*. This shaft 33 is intended to project outwardly of the front end of the casting 10 and cylinder block 6 for the purpose of being connected to a suitable source of power which will be described at a later point. Suitably keyed to this stub shaft 33 is a pinion 34 which is constantly in mesh with gears 35 and 36 which are suitably keyed to the crank shafts 27 and 28 respectively. It will now be seen that when the intermediate stub shaft 33 is driven, the crank shafts 27 and 28 will also be driven.

Positioned within the crank case 5 is the usual crank shaft 37 having crank portions to which the pitmans 38 are connected. The upper end of these pitmans 38 are suitably connected to the power pistons 39, as shown.

A suitable mechanism for driving the intermediate stub shaft 33 may be suggested as consisting of a sprocket gear 44 mounted upon the projecting end of the main crank shaft 37 and a sprocket gear 45 mounted upon the projecting end of the stub shaft 33 with a sprocket chain 46 operatively connecting the same. With such a mechanism, it will be seen that the piston valves 31 and 32 may be properly operated in unison with the main crank shaft 37 and that all of the said operative, movable parts will be positively connected.

The water jacket 8 surrounding the power cylinder 7 was previously referred to as being open at its upper end. The lower part 10 of the cylinder head is provided with a water jacket 40 which surrounds the explosion chamber 16, the valve cylinders 21 and 22, the passages 23 to 26, and the throat 17. This water jacket 40 communicates, as at 41, with the water jacket 8 and is intended to receive the water that has been heated, while cooling the cylinder block 6. It will be seen that the presence of heated water in the water jacket 40 will greatly aid in heating the incoming fuel and the explosion chamber 16 and will thereby assure the feeding of warm, dry, explosive mixtures to the explosion chamber 16.

For the purpose of lubricating the valves 31 and 32 and their operating mechanism, a pipe 42 is provided which extends from the interior of the inverted pan-shaped upper part 11 of the cylinder head to an oil pump 47 which is driven by a shaft 48 geared at 49 to the valve operating shaft 28. In this way, lubricant is fed from the crank case 5 into the cylinder head. For the purpose of maintaining this lubricant at a constant predetermined level, an overflow pipe 43 projects into the upper part 11 of the cylinder head and is intended to extend downwardly to empty into the

crank case 5. With this arrangement of elements, the piston valves 31 and 32, the crank shafts 27 and 28, the pitmans 30, the pinion 34, and the gears 35 and 36 will be 5 constantly lubricated.

In view of the fact that the explosion chamber 16 and restricted passage or throat 17, between such chamber and the power cylinder, constitute exceptionally novel 10 structure, it is believed advisable to set forth the utility of this arrangement of elements. The provision of the inverted cup-shaped pocket or recess 15 as an extension of the power cylinder 7, and the 15 combustion chamber 16, are for the purpose of providing an unusually large compression area. The purpose of employing such a large compression area is that I intend to use a super-charger or explosive mixture 20 compressor as suggested by my co-pending application, Serial No. 688,114, filed January 23, 1924. This application involves a compressor that is adapted to be interposed between a combustion engine and a 25 carburetor for delivering fuel to the intake valves under a greater pressure than the atmospheric pressure produced by the suction of the pistons within the engine. By employing such a compressor in combination 30 with the elements designated as 7, 15, 16, and 17, the actual content of explosive gas present in the power cylinder, or in operative communication therewith, at the 35 end of the suction or intake stroke of a power piston will be considerably greater than it would, with the engine at high speed, were such a combination not used.

The restricted passage 17 is for the purpose of creating atomic turbulence of the gas 40 content in the explosion chamber 16 during all of the compression stroke, up to the time of firing and directing such turbulence action, in its greatest intensity, toward the spark plug, used as a means of firing. It 45 is my claim that this will permit of complete combustion and an even flame and thereby increase the impact of explosion against the head of the power piston.

It is now believed that the construction 50 and operation of the various elements embodied in this invention will be completely understood without any further explanation of the same.

It is to be understood that the form of 55 this invention herewith shown and described is to be taken as the preferred example of the same, and that various changes in the shape, size, and arrangement of parts may be resorted to without departing from the 60 spirit of the invention or the scope of the subjoined claims.

Having thus described the invention, I claim:—

1. In a device of the class described, the 65 combination with a power cylinder, of a

cylinder head carried thereby, a pair of spaced valve cylinders in said head, a fuel inlet passageway leading to one of said valve cylinders and an exhaust passageway leading from the other valve cylinder, an 70 explosion chamber in said head, a reduced passageway between said power cylinder and said explosion chamber, a port connecting each of said valve cylinders with said explosion chamber, and a reciprocating valve 75 for controlling the flow through of said valve cylinders.

2. In a device of the class described, the combination with a power cylinder, of a cylinder head carried thereby, an explosion 80 chamber in said head above said power cylinder, a restricted open passageway between said power cylinder and said explosion chamber, a valve cylinder positioned on each side of said explosion chamber, passageways between each of said valve cylinders and said explosion chamber, a passageway leading outwardly of said cylinder head for each of said valve cylinders, and a valve in each of said valve cylinders for opening and closing 85 the passageways associated therewith.

3. In a device of the class described, the combination with a power cylinder, of a cylinder head mounted thereon, an explosion chamber in the cylinder head directly 90 above the power cylinder, a restricted passage between the explosion chamber and the power cylinder, a valve cylinder positioned laterally on each side of said explosion chamber, a passage between each of said valve cylinders and said explosion chamber, a passage leading outwardly of said cylinder head from each of said valve cylinders, a water jacket surrounding said power cylinder, and a water jacket in the cylinder head surrounding the explosion chamber, valve 95 cylinders, and passages and communicating with the water jacket surrounding the power cylinder.

4. In an internal combustion engine, an explosion chamber, a pair of vertically extending diametrically opposed valve cylinders associated with said explosion chamber, a separate passageway between each valve cylinder and the explosion chamber positioned between the ends of said cylinders, a passageway leading outwardly from the lower end of each valve cylinder a piston valve in each cylinder adapted to close the 110 passageways associated therewith, a power cylinder, and a restricted passage between the explosion chamber and the power cylinder thru which the exploded and unexploded gases pass to and from the power cylinder.

5. In a device of the class described, the combination with a cylinder block of a cylinder head carried thereby, said cylinder head comprising a cast lower part and an inverted pan-shaped upper part, piston 120 valves reciprocally mounted in the lower part,

4

valve operating mechanism in the upper part, means for connecting the said valves with said mechanism, igniting means carried by the lower part, and a tubular bolt separably connecting said part and positioned with the bore of said bolt axially aligned with said igniting means for permitting an electric wire to be connected to the latter.

6. The combination with a cylinder block 10 of a cylinder head carried thereby, said cylinder head comprising a cast lower part and an inverted pan-shaped upper part, piston valves reciprocally mounted in the lower part, valve operating mechanism in the upper part, means for connecting said valves with said mechanism, and means for separably connecting said cylinder head parts.

7. In a device of the class described, a cylinder block, a cylinder head carried thereby and comprising upper and lower parts, 20 an explosion chamber in the lower part, a well formed in the lower part above the explosion chamber, an internally threaded passageways leading from the bottom of the well to the explosion chamber, ignition 25 means threaded in said passageway and projecting into said well, and a tubular bolt connecting the upper part of the cylinder head to the lower part and having its bore communicating with said well to permit an 30 electric wire to be connected to the igniting means.

In testimony whereof I affix my signature.
JAMES I. GEMMILL.
